(57) **CLAIM**

The ornamental design for a lavatory cleansing block, as shown and described.

DESCRIPTION

The patent or application file contains at least one drawing executed in color. Copies of this patent or patent application publication with color drawings will be provided by the Office upon request and payment of the necessary fee.

FIG. 1 is a top view of a lavatory cleansing block showing my new design;

FIG. 2 is a bottom view thereof;

FIG. 3 is a first side view thereof;

FIG. 4 is a second side view thereof; and,

FIG. 5 is a top and side perspective view thereof.
